UNITED STATES PATENT OFFICE.

TIMOTHY P. CASTLE, OF QUINCY, ILLINOIS, ASSIGNOR TO COMSTOCK-CASTLE STOVE COMPANY, OF QUINCY, ILLINOIS, A CORPORATION OF ILLINOIS.

DESIGN FOR A HEATER.

Application filed October 16, 1926. Serial No. 19,389. Term of patent 14 years.

To all whom it may concern:

Be it known that I, TIMOTHY P. CASTLE, a citizen of the United States, residing at Quincy, in the county of Adams and State of Illinois, have invented a new, original, and ornamental Design for Heaters, of which the following is a specification, reference being had to the accompanying drawing, forming part thereof.

In the drawing:

Fig. 1 is a front view of the heater, showing my new design; and

Fig. 2 is a side view thereof.

I claim:

The ornamental design for a heater, as shown.
